BOTTLE WRAPPING DEVICE

Walter A. Emery, Wayne, Nebr.

Application July 12, 1940, Serial No. 345,130

4 Claims. (Cl. 93—2)

My invention pertains to a device for applying a wrapper to a bottle.

An object of my invention is to provide a simplified device which will apply a specially shaped wrapper to a moistened bottle surface, so that the bottle can be grasped without moistening the hands, etc.

A further object of my invention is to provide a device which will receive the wrapper and, incidental upon downward motion of the bottle, will cause the wrapper to be affixed snugly against the bottle sides, and leaving a certain visible area remaining so that the height of the bottle contents can be observed.

A further object of my invention is to provide an arrangement of this character which includes resilient means which are attached to suitable frameworks so that such resilient means will snugly carry the wrapper upwardly around the sides of the bottle and will then compress the wrapper upon such sides.

A further object of my invention is to provide an arrangement wherein a series of wrappers can be attached to a certain form of the device and wherein the wrappers will be removed individually therefrom.

A further object of my invention is to provide a very simple structure which requires a minimum of parts and can be manufactured at a very reasonable cost.

With these and other objects in view, my invention consists in the construction, arrangement, and combination of the various parts of my device, whereby the objects contemplated are attained, as hereinafter more fully set forth, pointed out in my claims, and illustrated in the accompanying drawings, in which:

Figure 1 is a side elevation of the device and taken in section along the lines 1—1 of Figure 2.

Figure 2 is a plan view of the arrangement,

Figure 3 is a developed view of the wrapper,

Figure 4 is a side elevation of a bottle after the wrapper is attached thereto,

Figure 5 is a detail of a slightly modified form,

Figure 6 is a modified form,

Figure 7 is a plan view of Figure 6, and

Figure 8 is a sectional view taken along the lines 8—8 of Figure 7.

The wrapper employed in my invention is indicated by the character 10 (see Fig. 3) and includes the central restricted portion 11 and the end portions 12 having the extending marginal flaps 13. The wrapper itself can be made of thin, slightly absorbent paper which is soft enough

for the purpose intended. The device for attaching the wrapper comprises the circular or otherwise shaped base member 14 in which is formed the square recess 15. Pivoted within the recess 15 and upon the bottom 16 thereof are the respective frames 17 and 18. The frames 17 can be made of suitable, fairly heavy wire material which comprises a pair of spaced parallel bars 19 which continue into the integral right-angled portions 20 which, in turn, are bent into the U-shaped formation 21. The member 21 (see Fig. 1) extends upwardly substantially at right angles to the plane of the members 19 and terminates into the arcuate portion 22. Similarly, the frame 18 includes a pair of parallel side bars 23 which extend into the portions 24 which lie adjacent to the members 20, and the members 24 also merge into the U-shaped portion 25 which is slightly less in width than the member 21 so that it can pivot within the member 21, and the member 25 also extends into the upper arcuate portion 26, which portion 26 is pivoted at 27 to a thin plate 28 which can be circular and which plate 28, however, rests upon the arcuate portion 22.

A further rubber member 29 is attached above the plate 28, which rubber member is in the shape of a spherical segment and is adapted to follow the circular contour beneath the base of the bottle. The members 20 and 24 are adapted to freely pivot within the staples 30 which straddle these members and hold them against the base 16. Suitably attached between the spaced bars 19 and 23 are a series of resilient and fairly loosely engaged attenuated rubber members 31 which can be fitted in suitable slots in the bars or can be attached in any other manner. The distance between the pairs of bars 19 or 23 is slightly greater than the bottle diameter. The bottle is indicated by the character 32.

In using the device, the wrapper 10 is first placed in the position shown in Fig. 1 with the portion 11 lying directly above the rubber arcuate member 29 and with the portions 12 lying against the frameworks 17 and 18 as shown. The bottle 32 is then pushed firmly downwardly in the direction of the arrow 33 which causes the arms 21 and 25 to rotate in the direction of the arrows 34 with the arcuate portion 22 sliding along the bottom of the plate 28. Correspondingly, the bars 19 and 23 will rise and rotate in the direction of the arrows 35 due to such pivotal action and, as a result, the bars will pass to a vertical position as shown by the dotted structure, and, at the same time, the resilient bands

31 will carry the portions 12 upwardly and around the bottle, the resiliency of such bands serving to firmly affix the paper member about the sides of the bottle.

Since the bottle is usually always moistened, the portions 12 and 13 of the wrapper will snugly adhere to the same, and when the bottle is drawn out of the device it will appear as shown in Fig. 4 with the wrapper attached thereto. A space will be remaining at 36 between the flaps 13 to allow visibility of the bottle contents. A slightly modified form is shown in Fig. 5 in which, instead of employing a series of bands 31, a single thin, highly resilient diaphragm member 37 is employed, which fills the entire space between the bars 23 or 19. The operation is the same in this type of structure. It will be noted from Fig. 1 that the sides of the cavity 15 permit a normal angular positioning of the bars 18 and 23 so that they will not be required to pass through too great an angle, thereby insuring a firm pressure at the top of the movement.

Figures 6 to 8 inclusive illustrate a further form of the apparatus in which several wrappers can be placed in the device at one time and removed individually. In this arrangement the parallel bars 38 extend into the portions 39 which are pivoted within the sockets 40, and the portions 39 extend into the U-shaped portions 41, the top portion of which is received within the suitable rectangular keepers 42 (see Fig. 6). Similarly a further pair of parallel bars 43 extend into the portions 44 which are pivoted within the sockets 45 and which portions 44 extend into the U-shaped portion 46 which portion is adapted to be received within the U-shaped member 41, and correspondingly being of lesser width. The sockets 40 and 45 are attached to an elongated base plate 47 which, in turn, is attached to the base ring 48 to provide a solid support. The keeper members 42 are attached to a further plate 49 and attached to the oval plate 49 at 50 is a resilient spring member extending into the spring arms 51 and which extend into the upwardly positioned portions 52 which portions 52 extend into the substantially horizontally positioned extremities 53 which are of reduced size and which terminate in the comparatively fine points 54.

Attached to the bars 48 and 33 are a series of fairly thick rubber flaps 55 which are attached along the bars at 56 and which flaps 55 extend inwardly a fairly substantial distance. Attached to the flaps 55 also are the rubber bands 57 which are attached to the band 58 which band 58 passes beneath the plate 49 and the spring member. A further pair of bands 59 are also attached to the flaps 55. This form of device is used in the following manner: Several plies of wrapper member 10 are laid upon the plate 49 with the center portions 11 resting on this plate. The several plies (see Fig. 8) are placed in this position and the spring-urged members 51 are urged upwardly and when the spring members are released the points 54 will be barely touching the edges of the central portion 11 of the wrapper 10, thereby serving to hold the same in fixed position. The wrappers can be adjusted so that the points are barely touching in the manner described along the edges thereof. The larger expanded portions of the wrapper will then lie as shown in Figures 6 and 7 and against the flaps 55.

When the bottle 32 is thrust downwardly, the U-shaped arms 41 and 46 will correspondingly

separate, bringing the bars 38 and 43 towards each other and, at the same time, bringing the portions 12 towards each other and about the bottle 32. The flaps 55 are of sufficient width to insure that a snug engagement is effected, since they cover an area wider than the bottle itself, and due to the slight bend of the arms 38 and 43 at 60 and since the pivots 45 and 40 are separated, the arms 38 and 43 will rise to a substantially vertical position, thereby causing the side portions 13 of the wrapper 10 to be firmly affixed about the bottle. As the bottle is removed from the device, the wrapper, which is attached, will tear away from the point 54 leaving the next outer wrapper in position for the next operation. The keepers 42 limit outward as well as inward movement of the U-shaped members 41 and 46, thereby maintaining the arrangement in cooperative position at all times and in proper balance. The torsion spring 61 brings the arms back to position.

It will now be seen that I have provided a simplified bottle wrapping device and wrapper which includes all of the advantages above mentioned and in my objects.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. A bottle wrapping device comprising two pairs of opposed parallel bars including pivoted adjacent extensions at right angles to the bars, said extensions including upwardly projecting portions adapted to receive a wrapping member thereon, whereby pressure of a bottle on said wrapping member and said upwardly projecting extensions will cause said parallel bars to swing toward each other and to draw the wrapping member upwardly and about the bottle, resilient means attached between the bars adapted to fold the ends of the wrapper around the bottle after said wrapper is brought into contact with the bottle as said parallel bars are pivoted toward each other.

2. A bottle wrapping device comprising two pairs of opposed parallel bars including pivoted adjacent extensions at right angles to the bars, said extensions including upwardly projecting portions adapted to receive a wrapping member thereon, whereby pressure of a bottle on said wrapping member and said upwardly projecting extensions will cause said parallel bars to swing toward each other and to draw the wrapping member upwardly and about the bottle, resilient means attached between the bars adapted to fold the ends of the wrapper around the bottle after said wrapper is brought into contact with the bottle as said parallel bars are pivoted toward each other, a base member to which said pivoted adjacent extensions are attached.

3. A bottle wrapping device comprising two pairs of opposed parallel bars including pivoted adjacent extensions at right angles to the bars, said extensions including upwardly projecting portions adapted to receive a wrapping member thereon, whereby pressure of a bottle on said wrapping member and said upwardly projecting extensions will cause said parallel bars to swing toward each other and to draw the wrapping member upwardly and about the bottle, resilient means attached between the bars adapted to fold

the ends of the wrapper around the bottle after said wrapper is brought into contact with the bottle as said parallel bars are pivoted toward each other, a base member to which said pivoted adjacent extensions are attached, a plate member slidably attached at the upper end of said upwardly projecting portions, said plate member receiving the wrapping member thereon.

4. A bottle wrapping device comprising two pairs of opposed parallel bars including pivoted adjacent extensions at right angles to the bars, said extensions including upwardly projecting portions adapted to receive a wrapping member thereon, whereby pressure of a bottle on said wrapping member and said upwardly projecting extensions will cause said parallel bars to swing

toward each other and to draw the wrapping member upwardly and about the bottle, resilient means attached between the bars adapted to fold the ends of the wrapper around the bottle after said wrapper is brought into contact with the bottle as said parallel bars are pivoted toward each other, a base member to which said pivoted adjacent extensions are attached, a plate member slidably attached at the upper end of said upwardly projecting portions, said plate member receiving the wrapping member thereon, resilient members attached to said plate having points engaged with the central portions of the wrapping sheets.
